UNITED STATES PATENT OFFICE.

GEORGE H. GILMAN, OF CLAREMONT, NEW HAMPSHIRE, ASSIGNOR TO SULLIVAN MACHINERY COMPANY, A CORPORATION OF MASSACHUSETTS.

CUTTING-TOOL.

1,382,777.

Specification of Letters Patent. Patented June 28, 1921.

Original application filed April 3, 1913, Serial No. 758,563. Renewed December 7, 1914, Serial No. 876,004. Divided and this application filed July 24, 1919. Serial No. 313,120.

To all whom it may concern:

Be it known that I, GEORGE H. GILMAN, a citizen of the United States, residing at Claremont, in the county of Sullivan and State of New Hampshire, have invented certain new and useful Improvements in Cutting-Tools, of which the following is a full, clear, and exact specification.

This invention relates to cutting tools, and 10 more especially to rock drilling machines of that class in which liquid and gaseous fluid may be supplied to the drilled hole to lay the dust, cleanse the hole, and expel cuttings therefrom, the present application being a 15 division of my prior application filed April 3, 1913, Serial No. 758,563; renewed December 7, 1914, Serial No. 876,004.

The objects of this invention together with 20 means whereby the same may be carried into effect, will best be understood from the following description of one form or embodiment thereof illustrated in the accompanying drawings, while its scope will be more particularly pointed out in the claims hereunto appended.

In these drawings,—

Figure 1 is a transverse sectional view, taken substantially on the line 1—1, Fig. 2, of a rock drilling machine embodying the 30 invention.

Fig. 2 is a central longitudinal section taken substantially on the line 2—2, Fig. 1.

Fig. 3 is a detail sectional view taken substantially on the line 3—3, Fig. 1.

Referring to the drawings, the invention 35 is, for illustrative purposes, therein shown as embodied in a mounted rock drilling machine of the indirect or hammer type, but it will be distinctly understood that many 40 of the features of the invention are applicable to machines of other types.

In the construction shown, 15 is a cylinder mounted upon the usual shell 16 and adapted to be fed toward or from the work by 45 means of a feeding screw 18. Working in the cylinder 15 is a hammer piston 20 adapted to deliver blows upon the inner end or shank of a suitable drill bit 23, said drill bit being hollow and comprising a suitable piece 50 of steel provided with a fluid supply passage 25 extending therethrough from end to end. As shown, the drill bit is provided with a plurality of lugs 26 by means of which it is held against rotative movement

with respect to, but permitted to move longitudinally within, a suitable holding device or chuck, herein shown as comprising a rotatable sleeve 27. Any suitable means, either manual or automatic, may be employed for rotating the drill bit, and suitable valve mechanism may be provided for controlling the flow of pressure fluid to and from the opposite ends of the cylinder to cause reciprocation of the piston. The distributing valve controls the admission of pressure fluid to opposite ends of the cylinder from a pressure fluid supply space 30, to which steam or other gaseous fluid, but preferably compressed air, is supplied by a flexible pipe 32 under the control of a throttle valve 48. 70 The drill bit rotating means and the distributing valve, however, form no portion of the present invention and are not illustrated herein as they may be of any usual construction well known in the art.

To supply the hollow drill bit with liquid and gaseous fluid under pressure, there is provided a supply tube 66 projecting loosely at its forward end into the bore of the drill bit and having its rear end extending into a 80 chamber 36 formed in a rear cylinder head or head block 37. The piston 20 is formed with an axial opening through which the tube 66 passes and reciprocates upon said tube with a sliding fit, so that no pressure fluid, or no substantial amount thereof, can pass through said axial opening from one end of the cylinder to the other. The rear end of the supply tube 66 is encircled by a 85 suitable packing ring 67 held under compression against the circumferential wall of the tube by a gland comprising a sleeve or bushing 68 in threaded engagement with the wall of the recess 36 in the head block 37, thereby clamping said tube in place in said 90 head block. Into the rear end of the chamber 36 is inserted a plug or nipple 39 having suitable provision for introducing water or other liquid into the supply tube, such 95 water being herein supplied under pressure from any suitable source by means of a flexible pipe 40 under the control of suitable means hereinafter described. The nipple 39 is provided with a tube or tubular extension 41 which projects coaxially into the rear end of the supply tube 66, but which 100 does not fit the bore of said supply tube but is held spaced therefrom by the nipple 39 to 105

provide an annular space 42 communicating with the interior of the sleeve or bushing 68 in the chamber 36. This chamber is connected by an annular groove 43 to a gaseous fluid supply port 44. The nipple 39 is provided with an axial passage 45 having communication, through a passage 46, with a port 47. During the operation of the tool, water may be admitted through the passage 10 45, said water passing centrally through the supply tube 66 and being united with the live air or other pressure fluid which enters the tube about the tubular extension 41 of the nipple. The relation of the tubular extension 15 to the supply tube is preferably such as to provide for a siphoning or ejector action, and the gaseous fluid and water, passing downwardly from the tube, are delivered to the bottom of the drilled hole through the 20 hollow drill steel.

In order that the supply of motive fluid to the cylinder, the supply of liquid to the drilled hole, and the supply of gaseous fluid to the drilled hole may be coördinately controlled, they are all preferably placed under the control of the single valve 48 which, in its closed position, shuts off entirely the supply of gaseous fluid and liquid from the tool, but which may be operated in such a manner as first to admit gaseous fluid to the drill bit, then to admit liquid to the drill bit while maintaining the supply of gaseous fluid, and finally to admit actuating fluid to the cylinder while still maintaining the supplies of 30 gaseous fluid and liquid to the drill bit. This will insure the operator against removing the drill steel from the machine before the hole is properly cleaned of its cuttings, and will also reduce the work of changing 35 the drill steel, inasmuch as the operator will not have to shut off the liquid and gaseous fluid in two separate operations.

To these ends the throttle valve 48 is provided with an interior chamber 49 communicating at all times with the air pipe line 32 through a suitable coupling 50, while the valve receives its supply of water from the water pipe line 40 through a suitable coupling 51. The couplings 50 and 51 are 45 herein shown in the form of elbows having tapered terminal portions 52 and 53, respectively, seated in correspondingly tapered bushings 54 and 54' threaded into the head block 37. The swiveled coupling 50 is held 50 seated in its bushing by a suitable spring 55 bearing at one end against the inner end of the throttle valve 48, the latter being also tapered, and the spring thus serving to assist the fluid pressure in keeping the valve firmly 55 seated in its chamber in the head block. In a similar manner the swiveled coupling 51 is held seated in its bushing 54' by a suitable spring 56 bearing at one end against the inner end of a water supply chamber 57 in 60 which the spring is placed. Leading from

the chamber 57 is a passage or port 58 which may be placed in communication with the port 47 by means of an arcuate groove 59 formed in the periphery of the valve 48. When the latter is closed, as shown in Fig. 2, the supply of water to the supply tube 66 is shut off, but when the valve is turned by means of a suitable handle 60 into the position shown in Fig. 3, the groove 59 serves to place the port 58 in communication with the port 47, thus admitting water to the supply tube. The valve 48 is provided with a port 61 leading from its interior chamber 49, and this port may be placed in communication with the pressure fluid supply space 30 to supply actuating fluid to the cylinder and the tool. A port 62 also leading from the interior chamber 49 in the valve, and incidentally communicating with the port 61, is provided to establish communication between the pressure fluid supply space 85 within the valve and the port 44 to admit gaseous fluid to the supply tube 66.

The groove 59 and ports 61 and 62 are so related to one another that by turning the valve in a counter-clockwise direction from the position shown in Fig. 2, pressure fluid is first admitted to the chamber 36 and to the interior of the bushing 68, and thence to the supply tube 66, causing a stream of the pressure fluid to be supplied through the hollow drill steel to the bottom of the drilled hole. When the valve is turned farther, the supply of pressure fluid to the supply tube is maintained and the groove 59 is brought into the 95 position to connect the ports 47 and 58, as shown in Fig. 3, so as to admit liquid to the supply tube. When the valve is turned still farther, pressure fluid is admitted to the supply space 30 and thence to the cylinder, while the supply of pressure fluid and liquid to the supply tube are still maintained. The valve may be closed by a reversal of the foregoing operations, thereby 100 shutting off first the supply of pressure fluid to the cylinder, then the liquid supply, and finally the supply of gaseous fluid to the tube.

In my improved construction it will thus be observed that a supply of liquid may be 115 delivered to the tube, and a supply of gaseous fluid may be delivered to the tube, so that the tubes may cause the desired mixture to be delivered to the drill steel, although it will be understood that other forms of controlling mechanism may be utilized for this purpose. It will also be noted that in my improved construction by removing the nipple or plug 39, the bushing 68, packing ring 67, and supply tube 66 may be all withdrawn 125 through the opening in the rear end of the head block 37, for purposes of repair or otherwise, without removing said head block or otherwise disassembling the apparatus.

While I have in this application specifi- 130

cally described one form which my invention may assume in practice, it will be understood that this embodiment is shown for illustrative purposes and that the invention 5 may be modified and embodied in various other forms without departing from its spirit or the scope of the appended claims.

What I claim as new and desire to secure by Letters Patent is:

10 1. In a rock drill, a rear head, a hollow drill steel, and means for supplying a cleansing fluid to said drill steel comprising a chamber in said head, a gland insertible in said chamber, retaining means between a 15 wall of said chamber and a wall of said gland, and a plurality of detachable fluid conducting means one of which is secured in said head by said gland and retaining means.

20 2. In a rock drill, a rear head, a hollow drill steel, and means for supplying a cleansing fluid to said drill steel comprising a chamber in said head, a gland insertible in said chamber, retaining means between a 25 wall of said chamber and a wall of said gland, and a plurality of fluid conducting tubes one of which is detachably secured in said head by said gland and retaining means, said gland and head having provision for 30 conducting a separate supply of cleansing fluid to each of said tubes.

3. In a rock drill, the combination with a cylinder, of percussive means therein, a hollow drill steel, a rear head, a plurality 35 of coaxially disposed tubular gaseous fluid and liquid conducting means mounted at their rear ends in said rear head, means between the rear ends of said conducting means co-operating with one of them to secure it in 40 said head, and a coaxially apertured securing member removable through said rear head.

4. In a rock drill, the combination with a rear cylinder head, of a plurality of coaxially disposed gaseous fluid and liquid conducting tubes in said head, means for securing 45 one of said tubes in position in said head comprising a member having a passage communicating with one of said tubes, and a second tube securing member having a passage communicating with the other thereof.

5. In a rock drill, the combination with a rear cylinder head, of a plurality of coaxially disposed gaseous fluid and liquid conducting tubes extending into the same, means 55 for securing one of said tubes in position in said head comprising a member having a passage communicating with one of said tubes, a second securing means having a passage communicating with the other thereof, and 60 a single valve controlling the flow through each of said passages.

6. In a rock drill, the combination with a cylinder, of percussive means therein, a hollow drill steel, a rear head, a plurality of 65 coaxially disposed gaseous fluid and liquid

conducting means disposed coaxially with said piston and mounted in said rear head, securing means having a passage leading to one of the same, and a coaxially disposed member for holding the other of said conducting means in position and having a passage leading thereto.

7. In a rock drill, the combination with a cylinder, of percussive means therein, a hollow drill steel, a rear head, a plurality of 75 coaxially disposed gaseous fluid and liquid conducting means disposed coaxially of said piston, means between the same for centering one of said means in said rear head and removable through said head, and a member 80 for holding one of said tubes in position axially alined therewith and likewise removable through said head.

8. In a rock drill, a cylinder, an axially apertured rear head therefor, an axially apertured piston in said cylinder, a plug closing the aperture in said rear head, a plurality of concentric tubes extending into the aperture in said head and disposed coaxially with said plug and the aperture in said 90 piston and removable rearwardly through the aperture in said rear head upon removal of said plug, and means including a passage through said plug for supplying fluid to one of said tubes.

9. In a rock drill, a cylinder, an axially apertured rear head therefor, an axially apertured piston in said cylinder, a plug closing the aperture in said rear head, a plurality of concentric tubes disposed coaxially with said plug and the aperture in said piston and removable through the aperture in said rear head upon removal of said plug, and means including a valve and passages 100 in said head and plug controlled by said 105 valve for supplying pressure fluid to one and liquid to the other of said tubes.

10. In a rock drill, a cylinder, an axially apertured rear head therefor, an axially apertured piston in said cylinder, a plug closing the aperture in said head, a plurality of tubes disposed coaxially with said plug and the aperture in said piston and removable through the aperture in said head upon removal of said plug, and means including a 110 single valve and separate passages controlled by said valve and formed in said head and said head and plug respectively for supplying pressure fluid to one and liquid to the other of said tubes.

11. In a rock drill, a cylinder, an axially apertured rear head therefor, an axially apertured piston in said cylinder, a tube extending into the apertures in said piston and head, a sleeve on the end of said tube 115 disposed in the aperture in said head, an axially disposed co-operating tube extending into the aperture in said head and into said first named tube, said tubes being removable rearwardly through the aperture in said 120 125 130

- head, and a plug normally closing the aperture in said head.
12. In a rock drill, a cylinder, an axially apertured rear head therefor, an axially apertured piston in said cylinder, a tube extending into the apertures in said piston and head, a sleeve on the end of said tube disposed in the aperture in said head, an axially disposed coöperating tube extending into the aperture in said head and into said first named tube, said tubes being removable rearwardly through the aperture in said head, a plug normally closing the aperture in said head, and means including passages through said head and plug for supplying separate supplies of cleansing fluid to said tubes.
13. In a rock drill, a cylinder, an axially apertured rear head therefor, an axially apertured piston in said cylinder, a tube extending into the apertures in said piston and said rear head, a short coaxially disposed coöperating mixing tube disposed in the aperture in said head and opening directly into the rear end of said first mentioned tube, and means for supplying separate supplies of pressure fluid and liquid to said tubes.
14. In a rock drill, a cylinder, an axially apertured rear head therefor, an axially apertured piston in said cylinder, a tube extending into the apertures in said piston and said rear head, a short coaxially disposed coöperating mixing tube disposed in the aperture in said head and opening into the rear end of said tube, means for supplying separate supplies of pressure fluid and liquid to said tubes, and means for removing said tubes rearwardly through the aperture in said head.
15. In a rock drill, the combination with a cylinder, a piston therein and a hollow drill steel, of separate coaxially disposed gaseous fluid and liquid conducting tubes mounted in said cylinder to conduct cleansing fluid for said steel, and removable means for holding said tubes in spaced relation in said cylinder.
16. In a rock drill, the combination with a cylinder, a rear head therefor, a piston in said cylinder, and a hollow drill steel, of separate coaxially disposed gaseous fluid and liquid conducting tubes to conduct cleansing fluid for said steel, and independent means in said rear head for holding said tubes in spaced relation.
17. In a rock drill, the combination with a cylinder, a rear head therefor, percussive means in said cylinder, and a hollow drill steel, of separate coaxially disposed gaseous fluid and liquid conducting tubes to conduct cleansing fluid for said steel, and means for maintaining said tubes in spaced relation comprising a member having lateral contact with one of said tubes and coöperating with the other thereof to limit its movement in one direction.
18. In a rock drill, the combination with a cylinder, a rear head therefor, percussive means in said cylinder, and a hollow drill steel, of separate coaxially disposed gaseous fluid and liquid conducting tubes to conduct cleansing fluid to said steel, and a clamping member disposed in said head into one end of which one of said tubes partially projects and through the opposite end of which a portion of said other tube projects.
19. In a rock drill, the combination with a cylinder, a rear head therefor, percussive means in said cylinder, and a hollow drill steel, of separate coaxially disposed gaseous fluid and liquid conducting tubes to conduct cleansing fluid for said steel, means for clamping the outer one of said tubes in said rear head comprising a member surrounding the same and extending rearwardly therefrom, and means for holding the inner one of said tubes in said rear head located to the rear of said clamping means.
20. In a rock drill, the combination with a cylinder having a rear head, percussive means therein and a hollow drill steel, of separate coaxially disposed gaseous fluid and liquid conducting tubes to conduct cleansing fluid for said steel, said tubes being mounted in the rear head of said cylinder and removable longitudinally rearwardly therethrough.
21. In a rock drill, the combination with a cylinder having a rear head, percussive means therein and a hollow drill steel, of separate coaxially disposed gaseous fluid and liquid conducting tubes to conduct cleansing fluid for said steel, said tubes being mounted in the rear head of said cylinder and removable longitudinally rearwardly therethrough, and means removable through the rear head of said cylinder for holding said tubes in position.
22. In a rock drill, the combination with a cylinder, a hollow drill steel and means carried by the cylinder and adapted to contact with the steel to deliver a blow thereto, of a plurality of cleansing fluid conducting means passing centrally through said cylinder, one of said conducting means terminating in the drill steel, and another of said conducting means terminating short of the end of said drill steel.
23. In a rock drill, the combination with a cylinder, a piston therein and a hollow drill steel, of separate coaxially disposed gaseous fluid and liquid conducting tubes to conduct cleansing fluid for said steel, said cylinder comprising a rear head in which said tubes are mounted, a packing surrounding one of said tubes, a member operative when said parts are in assembled relation to compress said packing, said member being provided with means for conducting fluid pressure to one of said tubes, and means coöperating with the other of said tubes to determine the forward position thereof.

24. In a rock drill, the combination with a cylinder, a piston therein and a hollow drill steel, of means for supplying cleansing medium to the drill steel comprising a rear head for said cylinder provided with a chamber therein, a conducting tube projecting into said chamber and extending longitudinally through said cylinder, a packing surrounding said tube and disposed in said head, a gland surrounding said tube and operative to compress said packing to hold said tube in fixed relation to said head, and a second tube mounted in said head to the rear of said first mentioned tube and projecting thereinto. 45
25. In a rock drill, the combination with a cylinder, a piston therein and a hollow drill steel, of means for supplying cleansing medium to a drill steel comprising a rear head for said cylinder provided with a chamber therein, a conducting tube projecting into said chamber and extending longitudinally through said cylinder, a packing surrounding said tube and disposed in said head, a gland surrounding said tube and operative to compress said packing to hold said tube in fixed relation to said head, said gland being provided with means for supplying cleansing fluid to said tube, and a second tube mounted in said head to the rear of said first mentioned tube and projecting into the latter. 50
26. In a rock drill, the combination with a cylinder having a rear head, percussive means in said cylinder, and a hollow drill steel, of separate coaxially disposed gaseous fluid and liquid conducting tubes to conduct cleansing fluid for said steel, and removable means disposed in said rear head for maintaining said tubes in fixed spaced relation. 55
27. In a rock drill, the combination with a cylinder having a rear head, percussive means in said cylinder, and a hollow drill steel, of separate coaxially disposed gaseous fluid and liquid conducting tubes to supply cleansing fluid to said steel, means disposed in said head and distinct therefrom into which one end of one of said tubes projects and which coöperates to maintain said tube in fixed relation to said cylinder, and means disposed to the rear of said first mentioned means for maintaining the other of said tubes in coaxial relation therewith. 60
28. In a rock drill, the combination with a cylinder having a rear head, percussive means in said cylinder, and a hollow drill steel, of separate coaxially disposed gaseous fluid and liquid conducting tubes to supply cleansing fluid to said steel, means disposed in said rear head and detachable therefrom into which one end of one of said tubes projects and which is operative to maintain said tube in fixed relation to said cylinder, and removable means disposed to the rear of said first mentioned means and coöperating to support the other of said tubes within said first tube. 65
29. In a rock drill, in combination, a head block, a throat piece therein, a fluid supply tube having its end in said throat piece, and a nozzle having its end adjacent the end of said tube, said throat piece, tube, and nozzle being normally fixed but separable with respect to said head block and each other. 70
30. In a rock drill, in combination, a recessed head block, a fluid supply tube communicating with the recess in said head block, and a nozzle having its end adjacent the end of said tube, said tube and nozzle being normally fixed but relatively adjustable. 75
31. In testimony whereof I affix my signature.

GEORGE H. GILMAN.
